(57) **CLAIM**

The ornamental design for a novel water surface skimming system, as shown and described.

DESCRIPTION

FIG. 1 is a perspective view of a novel water surface skimming system showing my new design;

FIG. 2 is a bottom perspective view thereof;

FIG. 3 is a top view thereof;

FIG. 4 is a bottom view thereof;

FIG. 5 is a back view thereof;

FIG. 6 is a front view thereof; and,

FIG. 7 is a side view thereof; opposite side view is a mirror image thereof.
